William Henry Atkinson, Inventor.
By John F. Hulstet, his Atty.

UNITED STATES PATENT OFFICE.

WILLIAM H. ATKINSON, OF LONDON, ENGLAND.

REFINING CAMPHOR AND APPARATUS THEREFOR.

SPECIFICATION forming part of Letters Patent No. 247,793, dated October 4, 1881.

Application filed March 28, 1881. (No model.)

To all whom it may concern:

Be it known that I, WILLIAM HENRY ATKINSON, a subject of the Queen of Great Britain, residing at London, England, have invented new and useful Improvements in Refining Camphor and in Apparatus therefor, of which the following is a specification.

This invention relates to improvements in the construction of apparatus employed in the refining or subliming of camphor, whereby the operation is rendered more easy, simple, safe, and economical, and whereby the camphor may be produced in bells, blocks, or slabs of any desired shape.

15 In carrying out my invention, instead of employing the ordinary glass vessels or flasks known as "bombolees," which serve for one operation only, I employ vessels or boxes made of iron or other suitable metal or material, and 20 provided with a removable cover, where necessary. The inner surface of the said vessel or box is provided with a removable casing or lining of thin sheet-lead or other suitable metal or alloy, a similar lining being employed for 25 the under side of the cover of the box or vessel.

To make my invention better understood, I will proceed to describe the same by reference to the accompanying drawings, in which I 30 have represented views of two forms of apparatus suitable for carrying out my invention; but it is to be understood that these forms of apparatus are merely for the purpose of illustration, and that other forms of apparatus may 35 be employed.

Figure 1 is a longitudinal section of a rectangular-shaped box or vessel with its removable lead lining, the cover being removed. Fig. 2 is a similar view, with the cover and its 40 lining placed over the open top of the box or vessel. Fig. 3 is a similar view, showing the method of forming the joint; Fig. 4, plan of Fig. 3. Fig. 5 is a sectional elevation, showing the improved apparatus constructed in the 45 form of the ordinary glass bombolo.

In Figs. 1, 2, 3, and 4, *a a a* represent a rectangular-shaped box, made preferably of suitable sheet metal, such as iron.

50 *b b* is the removable casing or lining of thin sheet-lead or other suitable metal or alloy, the

upper edges of the casing or lining projecting beyond the upper edges of the box, as shown.

c is the removable cover, having an opening, *d*, in any suitable position to allow of the escape of the steam, vapor, or heated air.

55

e is the lining of the under side of the cover.

To make use of the apparatus, the camphor to be refined or sublimed is placed in the lined box or vessel, Fig. 1. A sheet of lead, *e*, is then fitted to the cover *c*, and the cover *c* thus lined is placed on the box, as shown in Fig. 2. The projecting edges of the lead lining *b* and *e* are then lapped or doubled one over the other, as shown in Figs. 3 and 4, so as to form a tight joint. The apparatus is then placed in a sand-bath and the refining or subliming operation completed in the usual manner. As soon as the refined camphor shall have become cool the cover *c* is removed and the lead lining *b* and *e*, containing the refined camphor, is drawn 65 out of the box and the lead peeled from the camphor which it incloses, and the camphor is then trimmed in the usual manner. The vessel or box may be then relined for another operation.

70 The lead lining peeled from the camphor 75 may be rerolled, so that there is practically no waste of lead.

By the employment of my improved apparatus the refining or subliming operation is completed in less time than heretofore, and 80 with less cost of fuel and labor, as will be well understood.

The hereinbefore-described apparatus may be constructed with a jacket, to allow of superheated steam being employed in place of 85 a sand-bath, as will be understood without further description.

Fig. 5 shows the apparatus consisting of a vessel, *f*, of sheet-lead, constructed in the form of an ordinary glass bombolo, (by suitable 90 means, such as by the use of a form or templet constructed in parts, so as to allow of its removal from the interior of the vessel,) the lower half resting in a metal receiver or vessel, *g*. If required, the upper half may be inclosed 95 with a metal casing.

Having thus described my said invention and the best means with which I am acquainted for carrying the same into effect, I would have it understood that I do not confine myself to 100

the precise details herein laid down, as the same may be varied without departing from the peculiar character of the invention; but

What I do claim is—

- 5 1. The described improvement in the process of refining or subliming camphor, consisting in refining the same while surrounded by sheet metal or alloy, which may afterward be readily stripped from the refined cake, all substantially as shown and described.
- 10 2. The improved apparatus for refining or

subliming camphor consisting of a box or vessel having a lining of sheet metal or alloy, and with a cover having a lining of sheet metal or alloy, the projecting edges of these two linings 15 being adapted to be lapped or doubled one over the other to form a tight joint, substantially as shown and described.

W. H. ATKINSON.
